UNITED STATES PATENT OFFICE.

FRANK JAGER, OF CHICAGO, ILLINOIS.

CAR-DOOR.

1,143,122.

Specification of Letters Patent. Patented June 15, 1915.

Application filed November 11, 1912. Serial No. 730,632.

To all whom it may concern:

Be it known that I, FRANK JAGER, a citizen of the United States, and a resident of Chicago, county of Cook, and State of Illinois, have invented new and useful Improvements in Car-Doors, and of which the following is a specification, reference being made to the accompanying drawings.

My invention relates generally to doors, and has reference more particularly to that type of railway car door provided with a port and an outwardly swinging closure therefor, and which door is slideable longitudinally of the car to close the door opening.

One of the main objects of this invention is the provision of a movable means mounted at the side of the door opening adapted for movement to an operative position when the opening is closed whereby the door is held against sliding and the closure against outward swinging movement. Another object is the provision of such movable means designed to render a door of this character proof against leakage, and which may further present a series of broken joints against the entrance of water through interstices at points of vertical contact between car and door members.

A further object is the provision of novel coöperating members at the juncture of door and threshold designed to facilitate the unloading operation particularly when grain scoops are used to unload grain. A still further object is to provide improvements in this type of ported sliding door so as to effectually coöperate with the movable means to which reference has already been made.

These together with such other objects as may hereinafter appear or are incident to my invention, I attain by means of a construction illustrated in preferred form in the accompanying drawings, wherein:

Figure 1 is an elevation of the inside face of my improved door which is shown applied to a box car, the car body being broken away in order to accommodate the figure.

Figure 2 is a longitudinal sectional view of Figure 1.

Figure 3 is an elevation of the outside face of the door.

Figure 4 is a vertical section on the line IV-IV, and Figure 5 is a longitudinal sec-

tion on the line V-V respectively of Figure 3.

Figure 6 is a similar view of Figure 5, except that the door proper is shown at open position.

Figure 7 is a view in perspective of one of the pivoted angular jamb members in position against the door and door post and presenting a series of broken joints to prevent the entrance of water therebetween.

Figures 8 and 9 are detail views, slightly enlarged to better illustrate certain features of my invention.

My improved door is particularly adapted for use with cars engaged in grain carrying service, and entirely eliminates the necessity for employing temporary grain doors commonly used in such connection. To this end I provide an inside door provided with one or more ports suitably arranged therein for loading and unloading grain and other commodities, without having to slide the door proper longitudinally the car for the purpose of obtaining access to the car interior.

I preferably arrange one of the ports in a location sufficiently high enough for the reception of grain spouts, and of such width to fully provide for their effective manipulation to properly load the car. Another port is conveniently arranged at the lower end of the door for the quick unloading of grain by the usual scoops, or for the expeditious handling of ordinary way freight. A centrally located port may also be arranged in the door proper if desired for the unloading of such a commodity as coal, with a minimum expenditure of labor.

The ports extend substantially the width of the door opening, and are provided with outwardly swinging closures or doors having tight joints with surrounding door members. Each of the closures may be provided with any desired fastening means, which latter are relieved against excessive pressure from a load within the car by movable jamb members which are pivoted to suitable supports at the sides of the door opening. Each of the members has movement inwardly on a vertical axis from a position substantially out of the door and closure or closures to retain the former from sliding and the latter from outwardly swinging movement opening to a substantially right angular

position inwardly against the door. In the preferred construction, the inner angular faces of the movable jamb members are conformed to cover and rest in the angles formed by the contiguous outer faces of its support and door and continue laterally to the adjoining vertical edges of door and closures, and in this way desirably provide what might be termed a series of broken joints at these points extending vertically from the track beam to the threshold of the car and laterally from the support to the closures, in order to effectually prevent the entrance or percolation of any water or foreign substances between the car siding and the door, or between the door proper and the closures which cover the ports. These pivoted jambs as already referred above, furthermore constitute an additional means of support for the closures, particularly at their side portions.

In order to prevent grain scoops from catching on the ordinary type of lower guide track, I provide a track having an inner inclined surface so as not to obstruct or hinder the effective operation of such scoops, or whatever other means is adopted for unloading freight. This track also has its outer surface suitably perforated to register with apertures provided in the threshold of the car, so that in the event of any water collecting under the lower edge of the door it may be at once drained away.

In carrying out my invention as applied to a box car I provide an inside door 10 to close the door opening and comprising the horizontal rails 11 and upright frame members 12, the said door being suitably supported in the car by means of hangers 13 having sliding engagement with a track 14 bolted to the car lining or track beam 15 above the opening. The upright members 12 have their lower ends in sliding engagement with a lower rail 16 extending across the threshold 17, so that when pressure is applied to the door it is guided by the two tracks either to closed position against a cleat 19 when the members 12 are brought to rest up against the inside faces of the door posts 18; or conversely to open position to move clear of the door opening and behind a partition 33 which extends upwardly from the floor of the car to a point above the grain line of the car.

The conformation of the lower track 16 is clearly shown in Figure 9, said track extending cross the threshold from one door post to a point within the partition 33.

The track proper consists in an outer flat bearing surface 16^a, a longitudinal shoulder 16^b, an inner surface 16^c inclining upwardly from the floor to the shoulder but spaced away therefrom by a depression 16^d adapted to receive for sliding movement therein a downwardly depending flange or shoe 24

bolted to the lower portion of the door members 12. It will readily be seen that this lower track affords positive guiding movement to the door, so that when moved to closed position the members 12 are close up to and against the door posts, and at the same time it offers no abrupt angle to unloading means. The lapped edges of the lower closure and uprights 12 rest upon the surface 16^a and against the shouder 16^b, and in the event of any water collecting at this point, it is at once drained away by holes 25 provided in the flat surface 16^a and then through apertures, 26, cut through the threshold 17 to correspond therewith.

To form the ports or openings already referred to, I preferably employ three of the horizontal rails 11, suitably spaced away from each other and having their ends fastened to the two uprights 12, which latter being of greater relative thickness than the rails with the exception of that portion of the upper rail resting against the track beam 15 above the door opening, project slightly outward beyond the vertical plane 90 of the outer surface of the other door members.

Hingedly connected to the horizontal rails in the same vertical plane and adapted to have swinging movement to open and close the openings between the said rails and uprights are closures 20, 21, and 22 preferably provided centrally at their lower ends with any fastening means 23. The edges of the closure members are lapped to firmly seat 100 when in closed position on correspondingly recessed or lapped adjacent edges of the door rails and uprights to form tight joints, as 10^a, except the lapped lower edge 20^a of the closure 20 which rests against and seats 105 on the lower rail 16.

Referring now more particularly to Figure 3, it will be noted that the ports and their closures have slightly less width than the door opening to permit the easy manipulation of the said closures and it is apparent that when the door is closed the uprights 12 which rest against the door posts 18 each preferably present an angular abutting surface indicated at 12^a, inasmuch as the uprights are relatively thicker and do not lie in the same vertical plane as the other door members and closures. These abutments hold the door proper slightly away from the door posts and car lining members so that when the door is moved the latter will offer no obstruction to any fastening means thereon.

Pivotedly mounted in the doorway to each of the door posts and vertically in a line 125 preferably intermediate each of their inner and outer faces, is a movable weather jamb 28 of angular shape extending from the track beam to the threshold of the car, having a plurality of flanged surfaces as shown 130

in the preferred manner in Figure 8, thus providing a series of angular surfaces to fit in and protect whatever angles are formed by the various members in contiguity at the 5 sides of the door opening.

The outer flange 29 and inner flange 30 of the jamb 28 are oppositely disposed to each other, and intermediate these said flanges and forming the preferred connection therebetween is an angle iron portion 31, the inner flange 30 being pivoted to a web 32 secured to the door post 18. Formed on the free edge each of the flanges 29 is a lug 37 slotted to receive a staple 38 on the 15 door proper, the lug being clamped thereto by the usual seal pin 39.

When the door is closed, and the jamb given inward movement to a lateral position with respect to the door, the inner flange 20 30 rests against the door post, the outer flange 29 bears against the adjacent vertical edges of the closures and door and incidentally against other portions of the door members in vertical alignment therewith, 25 and the connecting portion 31 together with the flanges form a continuous cover or seal to joints or at points of contact between the various members forming the angle at the side of the door opening, and particularly 30 between the door and door post.

The outer edge of the lug 37 is slightly bent outwardly to provide a hand-hold for the easier operation of the jamb member, and should it bind in its outward movement by reason of pressure from within the 35 car, a tool may be inserted at this point in order to obtain the desired leverage. To permit full outward movement of the jamb to a position entirely clear of the door opening, I recess the outer face of the door port 40 at 18^a to receive the inner portion 31 of the jamb, and it is also suitably cut away to accommodate the bend edge of the lug. The employment of such metallic angular member 45 at both sides of the doorway and in this the weakest part of freight car construction is particularly advantageous. The lower extremity of the jamb may be flanged outwardly if desired, said flanged portion 50 being adapted to rest upon the threshold to shed water.

It will readily be seen that irrespective of the fastening means 23 the closures are held down in closed position tight on their 55 respective seats, the said fastening means being necessary only where the car is loaded with grain or like commodities possessing some degree of fluidity, checking any involuntary opening of the closures at a time 60 coincident with the outward movement of the jambs, as will be understood.

The door opening has easy movement along the tracks and when it becomes necessary to slide the door proper for the loading 65 or unloading of bulky freight, any pos-

sible obstruction by shifted freight to this opening movement is obviated by the partition 33 which is spaced away by the supporting uprights 34 and 35 from the car lining to accommodate the entire door when 70 open.

When the door proper is closed and grain is being loaded into the car through the upper port in the door, no leakage of grain through any interstices formed by warping 75 of door posts, or other members, can possibly occur before closing of the movable jambs, inasmuch as the rear end of the door is entirely inclosed by the partition and its supporting uprights 34 and 35, and furthermore the cleat 19 adequately protects the 80 front end of the door. Access to the partition is permitted through an opening at its lower end, normally closed by a swinging door 36.

From the foregoing, it is plainly evident that in my improved construction, all horizontal joints or points of contact between door members and closures are lapped, providing what might be termed a watershed 90 in this respect, and all vertical joints are not only lapped but they are in addition covered and protected against the entrance of water. This door is positively tight 95 against severest weather conditions, is durable in construction and has no involved parts to get out of order.

Having thus described my invention and illustrated its use what I claim as new and desire to obtain by Letters Patent is the following:—

1. In a railway car having a doorway frame and a doorway opening, the combination of a sliding door for said opening having a port, an outwardly opening closure member for said port hingedly mounted on said door and of a lesser width than the doorway opening, and an inwardly swinging holding member for holding said closure member in closed position, said holding 105 member being pivotally supported on the frame at a point appreciably removed from the face of the closure member and adapted when swung inwardly to lie between the closure member and the point of pivotal support and laterally thereof to engage the door and closure member whereby to hold the former against sliding and the latter from swinging outwardly when subjected to pressure.

2. In a railway car having a door post at each side of the doorway opening, a door mounted to close the opening and comprising a slideable frame and an outwardly swinging relief door of lesser width than the doorway opening, the door when in closed position having its frame resting up against the inner faces of the door posts, and means adapted to engage the swinging 125 door to hold the same from swinging and 130

the frame from sliding, said means consisting of a hinged jamb member mounted on either of the door posts to have movement on an arc in the doorway to occupy a lateral position with reference to the plane of the door, said jamb member being constructed to extend beyond the slideable frame and having a flanged or angular conformation substantially throughout its length and substantially coinciding with the angle formed by the door and door post; substantially as described.

3. In a box car having a door post at each side of the door opening, of means for closing the opening comprising a slideable frame and an outwardly swinging relief door of lesser width than the door opening, said slideable frame including side members between which the door is hung and which are adapted to rest up against the door posts, a guiding means positioned across the door opening in guiding relation with the frame and constituting a seat for the lower edge of the door, and a lock and closure means pivotally mounted on either of the door posts for swinging inward movement to overlap the meeting faces of door post and its adjacent side frame member and engage the edges of the relief door to hold the same against its seat, substantially as described.

4. In a freight car having a door opening and a door to close the opening, of a track or rail mounted on the threshold of the car to guide the door, having a raised portion and a depressed portion throughout its length, a flanged member on the lower end of the door fitting over the raised portion and slidably received in the said depressed portion of the track, said track being further provided with an integral longitudinal inner portion inclining upwardly from the threshold to the raised portion but spaced away therefrom by the said depressed portion.

45 5. In a railway car, the combination of a doorway frame and its opening, a door for the opening having a plurality of ports and closures therefor, a jamb member pivotally hung on the doorway frame and provided with a locking portion adapted to engage the said closures and maintain the same against their seats, and a sealing device for engaging the said locking portion whereby the closures are locked and sealed; substantially as described.

6. The combination with a car having its siding provided with a door opening, of means for closing the opening comprising a slideable frame and an outwardly swinging door in said frame spaced away from the siding and of lesser width than the door opening, said frame having a side member projecting outwardly beyond the plane of the door to close the space between the door and the siding, and a closure jamb member

mounted on the siding for inward swinging movement to a position where it projects over the said projecting side member, said jamb member being constructed and arranged to engage the said means to hold the swinging door against outward swinging movement and the frame from sliding, substantially as described.

7. In a railway car having a doorway frame and a doorway opening, the combination of a slideable door for said opening having a port, an outwardly opening closure member for said port subject to load pressure from within the car, and an inwardly swinging member for holding said closure member against said pressure pivotally supported on the frame at a point removed from the face of the closure member and adapted when swung inwardly to lie between the closure member and the point of pivotal support substantially at right angles to the closure member, and means on said holding member for preventing the door from sliding.

8. In a railway car having a doorway frame and a doorway opening, the combination of a slideable relief door for said opening having a port formed within a portion of its frame and wholly bounded by it, a closure member for said port adapted to seat in said frame portion and hingedly mounted therein for outward swinging movement away from its seat, an inwardly swinging holding member pivotally supported on the doorway frame at a point appreciably removed from said closure member and adapted when swung inwardly and laterally against the doorway frame to engage the closure member and hold the latter closed against its seat, and means co-operating with said holding member adapted for preventing the door from sliding.

9. In a railway car having a doorway, the combination with a door post adjacent thereto, of a leaved door for closing the doorway and mounted to open outwardly on a substantially horizontal axis, the leaves of the door being hinged together, and a movable jamb member hinged to the door post on a substantially vertical axis and adapted to swing out of the way when the door is open and against the door when the latter is closed, the said jamb member extending across adjacent edge portions of the leaves of the door, whereby the leaved door is held closed against pressure from within the car.

10. In a box car having a doorway frame and opening, the combination of a door for the opening provided with a port therein and a closure therefor, and means capable of holding the said closure on its seat against load pressure from within the car comprising a holding member hingedly mounted at the side of the doorway for inward swinging movement to positively engage with the

said closure and frame, the load pressure tending to further maintain the hinged member in its inward position.

11. In a railway freight car, the combination of a doorway frame and its opening, of a door adapted to have sliding movement longitudinally of the car to close the opening, said door being provided with a port and an outwardly swinging door to close the port, and a movable post pivoted in the doorway for movement to take up an operative holding position where it holds the second door on its seat, said member having locking means engaging with one of said doors to hold the first door against sliding movement.

12. In a railway freight car having a door opening and door posts at each side of the opening, a main door for the opening adapted when closed to rest up against the inner faces of the door posts, a supplementary door of slightly lesser width than the said opening hingedly mounted for outward

movement in a cut-away portion of said main door, and means for preventing leakage of grain or water past vertical meeting edges of both doors, comprising a pair of vertically extending jamb members, each pivoted on a door post at a point appreciably removed from the face of the second door for inward swinging movement to a position in the doorway against said door post and provided with an inner engaging portion designed to bear against and engage both doors so as to cover said vertical meeting edges, said members being further adapted to hold the second door against its seat in the main door.

In testimony whereof, I have hereunto signed my name in the presence of the two subscribed witnesses.

FRANK JAGER.
